UNITED STATES PATENT OFFICE

2,059,718

SIGNAL MEANS FOR RAIL CARS

Alfred O. Williams, Battle Creek, Mich., assignor
to Clark Tructractor Company, Battle Creek,
Mich., a corporation of Michigan

Application March 3, 1933, Serial No. 659,517

12 Claims. (Cl. 246—34)

The present invention relates generally to railroad equipment and is more particularly concerned with the provision of a new and improved signal means for rail cars and other vehicles employing cushioned supporting wheels or the equivalent.

Briefly, the principal object of the present invention is the provision of new and improved signal means embodying signalling apparatus carried on the car and means for establishing an electrical connection with the rail contacting tread portions of the cushioned wheels.

Another object of the present invention is the provision of a collector ring or the equivalent, adapted to be carried by the metallic rail contacting tread portion of a cushioned wheel, and suitable contacting mechanism and brush means carried by the car and adapted to be urged into and maintained in contact with the collector ring.

Another object of the present invention is the provision of a new and improved brush supporting means which is adapted to be carried by the car in insulated relation and to dispose the brush in contact or electrical connection with the metallic rail contacting tread portion of the wheel by means of a collector ring or the equivalent.

A further object of the present invention relates to improved means for biasing the brush for movement toward the collector ring so as to maintain a good electrical contact therewith at all times.

These and other objects of the present invention will be apparent to those skilled in the art after a consideration of the following detailed description of the preferred structural embodiment of the principles of the present invention, taken in conjunction with the accompanying drawings.

In the drawings:

Figure 1 is a vertical cross section taken through a cushioned rail car wheel of the type with which the present invention is principally concerned and illustrating one application of my improved signal means;

Figure 2 is a perspective, on a somewhat larger scale than Figure 1, illustrating one form of brush and brush holder and the bracket means supporting the same in position with respect to the wheel of the rail car and associated parts;

Figure 3 is a view similar to Figure 1 but illustrating a slightly different form of brush holder, corresponding to a section taken along the line 3—3 of Figure 4;

Figure 4 is a side elevation looking toward the

left in Figure 3, Figure 4 being on a somewhat larger scale; and

Figure 5 is a fragmentary detail, corresponding to a section taken along the line 5—5 of Figure 4.

Referring now more particularly to Figure 1, the reference numeral 10 indicates a cushioned rail car wheel in its entirety, the wheel 10 being supported upon bearings 12 of conventional construction carried by an axle housing 13 which is, in turn, connected with the side frame 14 of a 10 car truck. The detailed construction of the car truck or the wheel are not per se of any particular concern as far as the present invention is concerned. It is sufficient to note that the wheel 10 includes a spider or wheel body 16 constituting the hub portion of the wheel, and a metallic rail contacting tread portion 17, these wheel parts being suitably connected together by resilient cushioning means 20 disclosed and claimed in the copending application of Robert J. Burrows and myself, Serial No. 699,700, filed November 25, 1933, to which reference may be had for further details. The cushioning means 20 is arranged to absorb road shocks and the like, and generally for this purpose rubber members in the form 15 of annular rings or discs are employed. Since rubber is an insulating material it will at once be apparent that the metallic rail contacting tread or tire portion 17 is electrically separated 20 from the hub or wheel body portion 16 of the 25 wheel.

At the present time standard railroad equipment usually includes some form of signalling apparatus which utilizes predetermined sections of the track as electrical conductors and which 30 depends on the capacity of the wheels and axles of the rolling stock as short circuiting means to complete a circuit between the rails to operate the desired signals.

The available current in such systems is usually 40 limited and the potential between the rails is generally quite small, and it will therefore be recognized that whatever the short circuiting means is which is utilized to connect the two rails, such means must have a very low resistance. 45 Rails are practically always covered with a coating of oxide, due to atmospheric action and other causes, and the thickness of this coating depends, of course, upon the traffic to which the road bed is subjected and other factors. However, the 50 relatively great weight of standard rolling stock is sufficient to break down this coating when the train passes over the section of track incorporated in the signal system, so that the wheels and axles of such equipment can be used to establish 55

lish a short circuit between the rails having the required low resistance. For example, it has been determined that the wheels and axles of a locomotive have a resistance of approximately 0.06 5 of an ohm.

With the advent of light weight rail cars and the like it was shown that this equipment did not have sufficient weight to break through the outside coating so that when such equipment was 10 used on standard lines the customary signal circuits were not properly actuated. In order to overcome this undesirable feature, it has been proposed to employ apparatus carried by light weight rail cars and similar equipment, which 15 apparatus, taken as a whole in conjunction with the wheels and axles or the like of the rail car, serves as short circuiting means between the rails and having the low resistance required by the existing and more or less standardized signal 20 nailing apparatus.

The present invention is not concerned with the details of such apparatus and it is sufficient to note that one type of such mechanism comprises a source of alternating current carried by 25 the car and so interconnected with four of the truck wheels that a circuit is established which includes, in series, the two wheels on one side of the car and the intervening section of rail and the two wheels on the other side and the corresponding intervening section of rail. The purpose of this arrangement is to establish an alternating current circuit which embodies or includes a section of each of the two rails of the track, the effect of the flow of alternating current 30 through these sections being to break down the film of oxide on the rails and allow a flow of the conventional signal current of the railroad system. Thus, the auxiliary alternating current circuit, as a whole, constitutes a means of short 35 circuiting the two rails so that the relatively low voltage existing between the rails when the conventional railroad signal means is encountered will be sufficient to cause enough current to flow from one rail to another to properly actuate the signals.

Generally, the railroad signal current is direct current but sometimes the current employed in the rails for signalling means is alternating current. In this case, the alternator carried by the 50 rail car delivers the auxiliary alternating current through the wheels and short sections of the rails intervening therebetween at a frequency which is different than the frequency of the railroad signalling current employed. In this case 55 the apparatus carried by the rail car functions just the same as in the case where direct current is employed in the railroad signalling apparatus, namely, to function as a short circuiting means between the rails and having such a low effective resistance that a sufficient amount of signalling current can flow from one rail to another to properly operate the signals.

As stated above, the present invention is not primarily concerned with the means for establishing the auxiliary circuit of alternating current on the rail car, nor is the present invention concerned with the railroad signal circuits per se, these being a matter of common knowledge in the art. However, the present invention is 65 concerned with the provision of certain means especially useful in rail cars having cushioned wheels and aiding in conducting the auxiliary flow of alternating current from alternator on the car to the cushioned wheels so that the auxiliary circuit of alternating current including the 70

car wheels and the intervening sections of the track can be established. To this end, the present invention contemplates an arrangement including a brush and collector ring or the equivalent by which the auxiliary flow of alternating current can be directed to the tread portions of the cushioned wheels, which portions are in electrical contact with the rails of the track. 5

Referring now more particularly to Figures 1 and 2, it will be seen that the tubular axle housing 13 carries a brake support 23 welded or otherwise secured thereto and to which is anchored the braking shoes 24 which act, as desired, against a brake drum 25 carried by or rotatable with the hub 16 of the wheel 10. 10

The brake support 23 furnishes a convenient supporting means for the brush and brush holder by which current is lead to the metallic tread portion 17 of the car wheel. The brush holder, in its entirety, comprises a bracket supported 20 from the brake support 23 and serving, in turn, to movably support a carbon brush or the equivalent adapted to be engaged with a collector ring or the equivalent secured directly to the tread portion 17 of the wheel. The aforesaid bracket 25 comprises a supporting member 30 having a flange 31 adapted to be secured to the brake support 23 by cap screws 32 or the equivalent and a bracket arm section 34 connected with the flange portion 31 by suitable reinforcing webs 35 or the equivalent. The arm 34 is provided with a pair of laterally extending ears 36 which are apertured, as is the bracket arm 34, and these apertures receive rivets 37 by which a plate or block of insulating material 40 is secured to and 30 carried by the supporting bracket. 35

The brush holder proper comprises a depending hanger 42 having at each side laterally extending flange projections 43 separated by a recessed portion 44 which clears the head of the rivets 37 which are disposed in the bracket ears 36. The insulating plate 40 is provided with apertures adjacent the corners thereof for the reception of securing bolts 45 carried by suitable apertures in the laterally projecting flange portions 43. 40

The hanger 42 is formed with a pair of laterally spaced parallel walls 50 and 51 which are open along their upper edges and joined together at one end by a transverse wall portion 52. The 50 walls 50 and 51 are spaced apart so that when the hanger 42 is secured to the insulating plate 40 by the bolts 45, no part of the hanger 42 comes into contact with the intermediate rivets 37, and by virtue of the recesses 44 no part of the hanger 55 42 or its flanges 43 come into contact with the rivets 37 secured in the bracket ears 36. Thus, the hanger 42 is electrically separated from its supporting bracket means by insulating means having the required dielectric strength. 60

Adjacent the ends opposite the transverse wall 52, the hanger or bracket walls 50 and 51 are extended and terminate in apertured ear portions 55 and 56 which carry a pivot bolt 57, the latter serving to pivotally support a brush arm 60. Suitable means is provided for biasing the arm 60 for movement toward the plane of the wheel 10, and preferably this means takes the form of a spring 61 having an end engaged in an aperture 63, see Figure 2, in the transverse wall 70 52, the other end of the spring 61 being connected with an eye bolt 65 having a threaded end 66 extending through an aperture 67 formed in the brush arm 60 and provided with a threaded adjusting nut 68 by which the tension of the 75

spring means 61 can be adjusted. Preferably, the arm 60 is provided with pointed projections 70 and the hub 71 of the adjusting nut 68 is suitably notched, as at 73, to cooperate with the 5 projections 70 whereby the tension of the spring 61 serves to hold the adjusting nut 68 in any adjusted position. Also, this construction affords a form of knife edge support or connection between the biasing means and the arm 60 to 10 accommodate the angular movement of the pivotally supported brush arm 60.

The lower portions of the hanger or bracket walls 50 and 51 terminate in a cylindrical or sleeve portion 80 in which is slidably mounted a 15 tubular or cylindrical brush 81 formed of carbon or similar conducting material. The brush 81 has sliding movement in the sleeve portion 80 of the bracket 39 and is provided with a head 85 against which the outer end of the brush arm 60 20 is disposed. This end of the arm 60 is rounded, as at 86, and is received between a pair of flanges 87 carried by the head 85. A conductor cable 99 is welded or otherwise secured at one end to the brush 81 and is provided with a terminal 91 at 25 the other end which is bolted or otherwise secured to a binding post 92 on the insulated hanger 42.

As more clearly set forth in the copending application referred to above, the hub portion 16 is 30 secured to the rail contacting tread portion 17 by means of rubber cushioning members which are clamped under lateral compression by a clamping ring 93 and suitable clamping bolts 94. These bolts are carried by the metallic rail contacting tread portion 17 and can therefore be 35 utilized to secure a collector ring 95 to and in electrical contact with the tread portion 17 of the wheel. The collector ring 95 includes a flange portion 96 receiving the bolts 94 by means of 40 suitable apertures 97. The collector ring also is provided with a planar portion 99 against which one end of the brush 81 abuts, being held thereagainst by the force of the biasing means 61 45 acting through the brush arm 60. As best shown in Figure 1, the brush holder or bracket 30, in its entirety, is supported from the relatively stationary brake support 23 in such a position that the brush carrying portion 80 thereof is disposed adjacent the tread portion 17 of the wheel and 50 closely adjacent to the collector ring 95 thereof. It is to be understood, of course, that in certain instances the collector ring, as a separate element, may be dispensed with and the clamping flange 91 or some other part carried by the tread 55 portion 17 may be utilized as the equivalent of a collector ring. It is also to be understood that while the relatively stationary brake support 23 constitutes a convenient and easily accessible means for supporting the brush and brush holder 60 or bracket, any other part of the car may be utilized for this purpose within the scope of the present invention.

Figures 3 to 5, inclusive, are illustrative of a 65 slightly different form of brush support. In this form the bracket means including the securing flange 31 and the bracket arm 34 is identical with the form shown in Figure 2, and hence the same reference numerals have been utilized. Likewise, the insulating block 40 in Figure 3 is 70 substantially identical, for all practical purposes, with the form shown in Figure 2. In Figure 3, however, the insulating member 40 is shown as secured to the laterally projecting flange ears 36 by bolt means 110 instead of rivets, as in Figure 2. 75

The bracket hanger shown in Figures 3 and 4 is somewhat different from the form shown in Figure 2 and is designated in its entirety by the reference numeral 112. The hanger 112 comprises a transverse web 113 and laterally spaced 5 flanges 115 and 116. The upper portion of the hanger 112 is flanged, similarly to that shown in Figure 2, and includes laterally directed flange portions 43 separated by a recess 44 so that the hanger 112 can be secured to the insulating block 10 40 in electrically separated relation with respect to the supporting bracket arm 34.

The lower portion of the hanger 112 is extended laterally toward the wheel 10, as at 119, and this laterally extended portion is provided 15 with ears 120 or the equivalent spaced as shown in Figure 4 and each receiving a pivot pin 122, each pin being properly secured in place by a set screw 125 and a locking nut 126.

On each of the pivot pins 122 a brush arm 130 20 is mounted for swinging movement in a generally vertical plane. The portions of the brush arms receiving the pivot pins 122 are bifurcated, as indicated in Figure 5 by the reference numeral 131, the resulting ears 132 and 133 being aper- 25 tured to receive the pin 122. If desired, the set screw 125 and locking nut 126 may be provided on one of the ears of the brush arm rather than on the ear 120 on the brush hanger.

The end of each of the brush arms opposite 30 the ears 132 and 133 is provided with a recess 138 to receive a square carbon brush 140 or the equivalent, the latter being held therein by a closure plate 141 secured to the other end of the brush arm by cap screws 143. The closure plate 35 141 serves to effectively secure the brush 140 in the corresponding brush arm 130 in adjusted position therein. As the brushes wear, they may be readjusted by loosening the cap screws 143 and moving the brushes 140 to a new position. 40

Each of the brush arms 130 and the associated brushes are biased for upward movement by spring means 150 which includes a section 151 for each of the arms 130, the spring means 150 being anchored at its central portion to the laterally directed extension 119 of the hanger 112 45 by means of a clamping plate 155 and cap screws 156 or the equivalent. Electrical leads 160 are secured to each of the brushes 140 and are connected together and to the insulated bracket 50 hanger 112 by means of a binding post 161 and suitable locking nuts 162.

In the form shown in Figure 3, the collector ring is indicated by the reference numeral 170 and includes a cylindrical portion 171 having its 55 axis corresponding generally to the axis of the wheel 10. The cylindrical portion of the collector ring 171 is disposed adjacent the brake support 23 which, in this form as well as in the form of the invention shown in Figures 1 and 2, carries 60 the brackets supporting the brush means, and the laterally directed extension 120 on the bracket hanger 112 is disposed underneath the cylindrical portion 171 of the collector ring 170. This positions the brush arms 130 and the brushes 65 140 carried thereby underneath the collector ring so that the spring means 150, acting through the brush arms 130, serves to hold the brushes 140 in contact with the collector ring 170.

It is to be noted that, while in Figure 1 the 70 bolt means which secures the clamping ring to the tread portion of the wheel forms the means securing the collector ring to said tread portion, in Figure 3 the collector ring 170 is secured to the clamping ring 175 of the wheel by cap screws 75

176, which are separate from the clamping bolts 178 which secure the clamping ring 175 to the tread portion 17 of the wheel. Thus, in this form, the collector ring is secured in electrical 5 contact with the rail contacting tread portion 17 of the wheel by means separate from the means which secures the tread portion of the wheel to the hub portion thereof.

A source of alternating current or the equivalent is carried by the rail car and the operative 10 connections associated therewith may be electrically connected with the brush means described above by any suitable means, such means not forming any part per se of the present invention 15 has not been illustrated. For example, however, it is to be noted that the binding post 92 in Figure 2 or the binding post 161 in Figure 3 may be employed to effect this connection. If desired, of course, the cables 90 and 160 may be 20 lead directly to the associated apparatus on the rail car.

While I have described above the preferred 25 structure in which the principles of the present invention have been embodied, it will be apparent to those skilled in the art that my invention is not to be limited to the specific means shown and described above but that, in fact, widely different means may be utilized in the practice of the broader aspects of my invention.

30 What I claim, therefore, and desire to secure by Letters Patent is:

1. In a rail car, an axle housing, a cushioned 35 wheel journaled thereon and provided with a hub portion and a metallic rail contacting tread portion separated therefrom by cushioning means and movable relative to said hub portion, a collector member carried by and movable with said metallic rail contacting tread portion in electrical contact therewith, said cushioning means 40 serving to electrically insulate the rail contacting tread portion and selector member from said hub portion, a bracket supported by said housing and including a portion disposed adjacent said collector member, and brush means carried by said 45 bracket portion for collecting current from said metallic tread portion without causing the same to pass through the hub portion, said brush means being adapted to be maintained in electrical contact with said collector member while 50 accommodating the relative movement between said hub and tread portions of the rail car wheel.

2. Signal contact means for a rail car having a cushioned wheel with a hub portion and a metallic rail contacting tread portion movable with 55 respect to said hub portion, said contact means comprising, in combination, a collector ring connected to and movable with said tread portion relative to the hub portion of the wheel, a support carried by a relatively stationary part of the car 60 and disposed adjacent said collector ring, a block of insulating material carried by said supporting means and secured thereto, a hanger secured to said insulating block and extending closely adjacent said collector ring, and brush means carried 65 by said hanger in insulated relation from said supporting means and movable into contact with said collector ring, said brush means being movable relative to said hanger in the direction of relative movement between said hub and tread 70 portions.

3. Signal contact means for a rail car having 75 cushioned wheels with metallic rail contacting tread portions and a collector ring carried by one of said tread portions, said contact means comprising a bracket carried by a relatively station-

ary part of the car, an insulating plate secured thereto, a hanger connected with said insulating plate and extending to a point adjacent the tread portion of one of said wheels, said hanger comprising a member having a pair of apertured ears, 5 an arm pivotally supported thereby, brush means movably associated with said hanger and engaged by one end of said arm, and means for urging said arm toward said collector ring to carry said brush means into electrical contact there- 10 with.

4. Signal contact means for a rail car having a plurality of cushioned wheels, each having a hub portion and a metallic rail contacting tread portion separated therefrom by insulated cushioning 15 means, said contact means comprising a bracket carried by the car and disposed adjacent one of said tread portions, a collector ring carried by said rail contacting tread portion, a hanger carried by said bracket in insulated relation and including a sleeve portion extending to a point closely adjacent the collector ring carried by said tread portion, and a brush mounted in the sleeve portion of said hanger and shiftable into contact 20 with said collector ring. 25

5. Signal contact means for a rail car having a plurality of cushioned wheels, each having a hub portion and a metallic rail contacting tread portion separated therefrom by insulated cushioning 30 means, said contact means comprising a bracket carried by the car and disposed adjacent one of said tread portions, a hanger carried by said bracket in insulated relation and including a sleeve portion, a collector ring carried by said 35 tread portion, a brush mounted in the sleeve portion of said hanger and movable into contact with said collector ring, an arm pivotally supported from the hanger and having one end disposed against one end of said brush, and spring means reacting against said pivoted arm for bi- 40 asing said brush for movement toward said collector ring.

6. Signal contact means for a rail car having a plurality of cushioned supporting wheels, each of 45 said wheels including hub and tread portions separated by cushioning means, said contact means comprising a collector ring carried by the tread portion of one of said wheels and including a substantially cylindrical portion, a bracket supported by the car and having insulating means 50 thereon, a hanger supported by said insulating means and electrically separated from said car, said hanger including a pair of pivotally supported arms extending from the hanger in opposite directions, a brush carried at the outer end 55 of each of said arms and in a position to contact with the cylindrical portion of said collector ring, and spring means reacting against said hanger for urging said brushes into electrical contact with the collector ring. 60

7. Signal contact means for a rail car having a plurality of cushioned supporting wheels having electrically separated hub and tread portions, one of said tread portions including a metallic section and a collector ring secured thereto and provided 65 with an axially disposed cylindrical portion, said contact means comprising a bracket carried by the car and including a portion extending alongside the cylindrical portion of said collector ring, a brush arm pivotally carried by said bracket and 70 swingable toward and away from said collector ring, a brush carried by said arm in the plane of the cylindrical portion of said collector ring, and spring means for urging said arm toward the collector ring. 75

8. In a rail car having a cushioned wheel with a metallic rail contacting tread portion, brake means for the car including a relatively stationary brake support, a bracket connected with said 5
brake support and having a portion extending radially outwardly therefrom to a point adjacent the tread of the wheel, and brush means carried by said bracket portion and adapted to be disposed in electrical connection with said metallic 10
tread portion.
9. Signal contact means for a rail car having cushioned wheels with relatively movable hub and metallic rail contacting tread portions, said means comprising a collector ring carried by 15
and movable with the tread portion of one of said wheels, said collector ring having a cylindrical surface concentric with respect to the tread portion with which it moves, bracket means supported by the car in insulated relation and 20
disposed adjacent said collector ring, a brush holder pivotally connected with said bracket means, brush means supported in said brush holder and movable therewith in a generally radial direction with the cylindrical portion of said 25
collector ring, and spring means for maintaining said brush means in electrical contact with said collector ring irrespective of relative movement between the latter and said bracket means.
10. In a rail car having a cushioned wheel with 30
a metallic rail contacting tread portion, brake means for the car including a relatively stationary brake support, a bracket connected with said brake support, a collector ring carried by the rail contacting tread portion of said wheel and including sections extending inwardly to and disposed adjacent the radially outer portions of said brake support, and brush means carried by said bracket and adapted to be disposed in electrical connection with said collector ring sections. 5
11. In signal means for a rail car having a cushioned wheel with a metallic tread portion and a brake support carried adjacent the wheel, a contact supporting device comprising a supporting member having a flange adapted to be secured to said brake support and lugs disposed in a plane at right angles to said flange, an insulating plate secured to said lugs, a bracket portion, and means securing the latter in said plate and adjacent the tread portion of said wheel, 15
said means being out of contact with said member and said lugs.
12. In signal means for a rail car having a cushioned wheel with a metallic tread portion and a brake support carried adjacent the wheel, 20
a contact device comprising a supporting member having laterally directed lugs and a flange adapted to be secured to said brake support and disposed in a plane at right angles to the plane of said lugs, an insulating plate, means for securing said plate to said lugs, a brush holding bracket portion also having lugs spaced from said supporting member and the lugs thereof, and means out of contact with said first securing means and said first mentioned lugs for connecting the lugs of said bracket portion to said insulating plate so as to dispose said bracket portion adjacent the tread portion of said wheel. 25
- ALFRED O. WILLIAMS.
